DESIGN FOR A POWER UNIT FOR FOOD PREPARING DEVICES

Clarence J. Steinman, St. Louis, Mo.

Application August 5, 1935, Serial No. 57,965

Term of patent 14 years

To all whom it may concern:

Be it known that I, Clarence J. Steinman, a citizen of the United States, residing at St. Louis, in the State of Missouri, have invented a new, original, and ornamental Design for Power Unit for Food Preparing Devices, of which the following is a specification, reference being had to the accompanying drawing, forming part thereof.

In the accompanying drawing, Fig. 1 is a top plan view; and Fig. 2 is a view in side elevation of a power unit for food preparing devices embodying my new design.

I claim:

The ornamental design for a power unit for food preparing devices, as shown.

CLARENCE J. STEINMAN.
